US0D1097577S

(12) United States Design Patent (10) Patent No.: US D1,097,577 S
(45) Date of Patent: * Oct. 14, 2025

(54) SAFE CABINET STORAGE ORGANIZER

(71) Applicant: Juan Zheng, Guangdong (CN)

(72) Inventor: Juan Zheng, Guangdong (CN)

() Term: 15 Years

(21) Appl. No.: 29/804,904

(22) Filed: Aug. 23, 2021

(51) LOC (15) Cl. 06-04

(52) U.S. Cl.

USPC D6/552; D3/315; D3/319

CLAIM

The ornamental design for a safe cabinet storage organizer, as shown and described.

DESCRIPTION

FIG. 1 is a perspective view of a safe cabinet storage organizer showing my new design;

FIG. 2 is an bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in FIGS. 1, 3, and 7 illustrate portions of the safe cabinet storage organizer that form no part of the claimed design.

1 Claim, 8 Drawing Sheets
